UNITED STATES PATENT OFFICE.

GEORGE P. ABORN, OF BROOKLINE, MASSACHUSETTS, ASSIGNOR TO BLAKE & KNOWLES
STEAM PUMP WORKS, A CORPORATION OF NEW JERSEY.

ENGINE-VALVE.

1,102,180.

Specification of Letters Patent. Patented June 30, 1914.

Application filed October 19, 1912. Serial No. 726,829.

To all whom it may concern:

Be it known that I, GEORGE P. ABORN, a citizen of the United States, residing at Brookline, county of Norfolk, and State of Massachusetts, have invented certain new and useful Improvements in Engine-Valves, fully described and represented in the following specification and the accompanying drawings, forming a part of the same.

10 This invention relates generally to steam engines and pumps, and more particularly to engines equipped with fluid-actuated valves of the general class shown and described in Letters Patent to Hall, Nos. 15 737,609 and 737,610.

One object of the invention is to secure economy in steam consumption by working the steam expansively.

Another object, when the invention is used in connection with pumps, is to slow down the piston stroke near its end to allow the valves in the pump cylinder to seat quietly and with little shock, and to allow an easier reversal of the piston stroke.

25 Another object is to secure a simpler form of mechanism to effect these results than has hitherto been used; to reduce to a minimum the clearance spaces in the cut-off ports and the expansion of steam therein; 30 and a still further object is to secure an adjustable cut-off mechanism.

In the drawings, Figure 1 is a section transverse to the steam cylinder. Fig. 2 is a section longitudinally of the cylinder and 35 on the line of the valve rod. Fig. 3 is a plan of the valve seat on the steam cylinder showing port connections. Fig. 4 is a plan of the main slide valve, and Fig. 5 is a detail in plan of the cut-off valve gear and auxiliary valve.

In Fig. 1, the main cylinder is indicated at 10, and the main piston is partly shown at 11 in Fig. 2. The valve seat 12 of the main cylinder is equipped with three main ports, 13 and 14 being the inlet ports and 15 the exhaust port. The main slide valve 16 is moved by an auxiliary piston 17 enclosed in the auxiliary steam cylinder 18. The cylinder 18 is shown positioned at right angles to the axial line of the main cylinder which it surmounts, and this is the preferred arrangement although not essential to the broader features of the invention.

The central portion of the valve piston 17 55 is of a reduced semi-cylindrical cross-section

as shown in Figs. 1 and 2, and in the space thus formed between the valve piston and the main slide valve 16, the auxiliary valve 19 and the cut-off valve and gear 34, 46, 35, 47 are located. The auxiliary valve controls 60 the admission and exhaust to and from the valve piston and is moved by a shouldered block 48 forming a part of the cut-off valve gear between the shoulders of which the auxiliary valve is loosely inclosed. The 65 cut-off valve or valves 34, 35 control the supply of steam passing through the main valve and they are moved as a unit by valve rod 21, which is actuated in turn by the usual tappet arrangement, not shown. 70

As best shown in Fig. 2 and Fig. 5, the auxiliary valve is located within the divided cut-off valve. Both valves have their seats upon the upper face of the main slide valve 16, and their movement, in line with the 75 valve rod 21, is at right angles to the line of motion of the main slide valve 16 and the valve piston 17. The opening and closing of the ports of the auxiliary cylinder are determined by the combined movements of 80 the auxiliary and the main slide valves, as will presently be described. As shown in Figs. 2 and 5, the cut-off valves are shifted to regulate the point of cut-off by means of a hand wheel 44 which is keyed to a sleeve 85 43 which works in a bearing in bracket 46. In the end of the sleeve 43 is a block 42 having a square hole in its center through which slides the end of the valve rod 21, which is squared to fit this hole. On the 90 valve rod are fitted two split nuts 46, 47, one threaded righthand and the other lefthand. The cut-off valves 34, 35 engage with the flanges on the valve rod nuts 46, 47 and turning the valve rod moves the cut-off 95 valves together or apart according to the direction in which the valve rod is rotated. The valve rod is attached to the valve rod link by a swivel connection (not shown) to permit the rotation of the valve rod. A 100 pointer 45 indicates the point of cut-off upon a suitable scale.

Referring now to Fig. 3, the seat of the main slide valve is shown as being equipped with seven ports. These ports are the main 105 exhaust at 15, the two main inlets at 13 and 14, the two starting ports 22 and 23 controlled by the main slide valve, and the two ports 24 and 25 communicating with the auxiliary cylinder. As is obvious, the ar- 110

angement of these ports is such also as to secure in the usual way the preadmission of steam to prevent shock upon the beginning of a piston stroke in the main cylinder, the 5 pocketing of steam at the end of the stroke for the same reason, and also, by means of the related ports, to cushion the movements of the auxiliary piston 17.

The described mechanism operates as follows: Assuming the auxiliary piston 17, as viewed in Fig. 1, to be in its extreme right-hand position, as shown, it will be held in this position by steam admitted to the left of the auxiliary piston through ports 24, 24 10 as shown in Figs. 1 and 2. The main valve 16 will also be in a similar position and will allow steam to pass through ports 26, 27, 13 and 29 (Fig. 2) into the main cylinder 10, causing the piston 11 to move to the right. 15 At the same time steam will exhaust through port 14 (Fig. 1) to the cavity 30 in main slide valve 16 and the central exhaust port 15.

At a predetermined point in the travel of 20 the main piston 11, the usual tappet gear (not shown) will move the valve rod 21 to the right, as viewed in Fig. 2. The cut-off valve 34 attached thereto will thereupon close port 26, cutting off the supply of steam 25 to the main piston, thus causing the steam to work expansively during the remainder of the piston stroke.

As the cut-off valve closes port 26, the 30 shouldered block 48 carried by the valve rod 35 contacts with auxiliary valve 19, causing the latter valve to move to the right until port 25 in main valve 16 is open to steam and port 24 open to the exhaust cavity 31 in auxiliary valve 19. Steam is now exhausted 35 from the left of the auxiliary piston 17 through the channel indicated generally by 24, 24, while at the same time steam is admitted through the opposed ports indicated at 25. This causes the auxiliary piston and 40 main slide valve to move to the left until the port 24 in the main valve is closed to exhaust by the edge of the cavity 31 in the auxiliary valve 19. The port 24 being closed, the auxiliary piston cushions on the 45 steam confined between its end and the auxiliary cylinder head, and comes to rest with the main slide valve in the proper position for the return stroke of the main piston.

If it be desired to have the steam follow 50 full stroke in the main steam cylinder, as in warming up, it may be accomplished by moving the cut-off valves 34, 35 apart by handwheel 44. When the cut-off valves are 55 separated the maximum distance they will 60 not entirely close the cut-off ports during the stroke of the main piston.

The construction as thus shown and described is the preferred embodiment of the invention; but it will be understood that the 65 invention is not limited to the specific ar-

angement of parts illustrated, but that the broader features of the invention, as defined by the claims, may be embodied in other constructions.

The construction shown and described 70 herein includes certain features claimed broadly in my prior applications, Serial No. 659,501, filed November 10th, 1911 now Letters Patent No. 1,055,997; No. 659,968, filed November 13th, 1911 now Letters Patent No. 1,055,994; No. 686,562, filed March 27, 1912, now Letters Patent No. 1,055,996 and No. 686,563, filed March 27, 1912.

What is claimed is:—

1. In combination, a main slide valve, 80 fluid actuated means to move said valve, an auxiliary valve controlling the fluid actuated means, and an adjustable cut-off valve mechanism controlling both the movement of the auxiliary valve and the supply 85 of fluid to the main slide valve.

2. In combination, a main cylinder, a main slide valve, an auxiliary cylinder, an auxiliary piston located within the auxiliary cylinder and controlling the main slide 90 valve, an adjustable cut-off valve mechanism controlling the movement of fluid to the main slide valve, an auxiliary valve controlling the movement of fluid to the auxiliary cylinder, the said auxiliary valve being 95 controlled by the movement of the cut-off valve mechanism.

3. In combination, a main slide valve, fluid actuating means to move said valve, an auxiliary valve controlling the fluid actuated 100 means, an adjustable cut-off valve, and a valve rod moving both the auxiliary valve and cut-off valve.

4. In combination, a main slide valve, fluid actuated means to move said valve, an auxiliary valve controlling the fluid actuated 105 means, an adjustable cut-off valve, and a valve rod moving both the auxiliary valve and cut-off valve, the said cut-off valve being adjustable without affecting the position 110 of the auxiliary valve.

5. In combination, a main slide valve, fluid actuated means to move said valve, an auxiliary valve controlling the fluid actuated 115 means, an adjustable cut-off valve, and a single valve seat having ports for said auxiliary valve and cut-off valve.

6. In combination, a fluid actuated valve gear including an auxiliary cylinder, an auxiliary piston, a main slide valve attached to 120 and moved by the piston, an auxiliary slide valve, an adjustable cut-off valve, the said auxiliary slide valve and the cut-off valve being mounted upon the main slide valve and nested in said piston, but having their 125 respective movements independent of the piston.

7. In combination, a fluid actuated valve gear including an auxiliary cylinder, an auxiliary piston, a main slide valve attached 130

to and moved by said piston, an auxiliary slide valve, and an adjustable cut-off valve, the said auxiliary slide valve and the cut-off valve being mounted upon the main slide valve and located between the main slide valve and the auxiliary piston.

8. In combination, a main slide valve, fluid actuated means to move said valve, an auxiliary valve controlling the fluid actuated means, and an adjustable cut-off valve mechanism controlling both the movement of the auxiliary valve and the supply of

fluid to the main slide valve, the said auxiliary valve and cut-off valve mechanism being located between the fluid actuated means ¹⁵ and the main slide valve.

In testimony whereof, I have hereunto set my hand, in the presence of two subscribing witnesses.

GEORGE P. ABORN.
